UNITED STATES PATENT OFFICE.

ELWOOD B. AYRES, OF PHILADELPHIA, PENNSYLVANIA, ASSIGNOR TO PROCTOR & SCHWARTZ, INCORPORATED, OF PHILADELPHIA, PENNSYLVANIA, A CORPORATION OF PENNSYLVANIA.

DRIER.

1,376,244.

Specification of Letters Patent. Patented Apr. 26, 1921.

Application filed May 27, 1920. Serial No. 384,573.

To all whom it may concern:

Be it known that I, ELWOOD B. AYRES, a citizen of the United States, residing in Philadelphia, Pennsylvania, have invented 5 certain Improvements in Driers, of which the following is a specification.

My invention relates to certain improvements in driers of the type in which air is circulated through the drying chamber and 10 through the heating chamber by means of a fan.

One object of the invention is to provide a compact drier of this type, in which there are two drying compartments and a heating chamber common to both compartments. 15 A further object of the invention is to locate a single fan so that the circulation will be through both compartments.

In the accompanying drawings: 20 Figure 1 is a side view of my improved drier;

Fig. 2 is an end view, showing the doors open;

Fig. 3 is a plan view, showing the doors 25 open; and

Fig. 4 is a plan view, illustrating a modification of the invention.

Referring to the drawings, 1 is a casing, 2 is a heating chamber extending the full 30 height of the drier and having a series of heating coils 3 therein. In front of this heating chamber is a drying chamber consisting of two compartments 4, 4^a. 5 is a partition extending part-way between the 35 two compartments 4, 4^a, and into the heating chamber to a certain extent. 6 is a fan located at the rear end of the drying chamber 4 and mounted on a horizontal shaft 7 adapted to suitable bearings and provided 40 with a driving pulley 8, in the present instance. The front end of the drying chamber is supported on legs 9 suitably braced. The two compartments are provided with hinged doors 10 which are located at the 45 front end of the machine so that when open, access can be had to the full width of the drier. Within the drying chamber are vertical bars 11 to which are attached the tray supports 12, made of angle iron in 50 the present instance and spaced a sufficient distance apart so that a series of trays can be located in the two compartments, after which the doors are closed and power is applied to the shaft 7. The air is circulated 55 through the heating chamber, through the

drying compartment 4, returning through the drying compartment 4^a to the heating chamber.

13 is an exhaust pipe extending into the heating chamber near the drying compartment 4^a and is beveled at the forward end, as shown in Fig. 1, so that a certain amount of air is exhausted. As the air circulates through the heating and drying chambers, fresh air is taken into the heating chamber 60 through the pipe 14.

In the construction shown in Figs. 1, 2 and 3, there is no positive partition separating the heating chamber from the drying chamber. The heating coils are at the 70 rear end of the drying chamber, preferably extending the full width of the apparatus.

In Figs. 1, 2 and 3, I have illustrated the fan at one side of the apparatus so that the entire current of air passes into one 75 drying compartment and returns through the other drying compartment.

In Fig. 4, I have illustrated a modification, in which the fan 6^a is centrally located directly back of both drying compartments 80 and inclosed within a casing 15, so that when the fan is in motion the circulation, as indicated in Fig. 4, is in both chambers. The casing 15 is flared at 16 and terminates about the middle of each chamber. In this 85 instance, the air intake 14^a is at the rear of the casing and at one side of the fan, while the exhaust opening 13^a at the top is located at the forward end and centrally between the two drying compartments. In 90 this instance, the doors 10^a are at the side of the machine, and doors 17 are also provided at the side so that access may be had to the heating section of the apparatus.

An apparatus of the type described above 95 is intended as a general drier for drying articles, such as vegetables and fruits on trays. It is especially adapted where an economical small capacity drier is required.

I claim:—

1. The combination in a drier, of a drying chamber having two compartments located side by side; a heating chamber at the back of the two drying compartments and communicating therewith; means for heating 105 the air in the heating chamber; and a single circulating fan arranged to circulate air through both drying compartments and the heating chamber.

2. The combination in a drier, of a casing; 110

a drying chamber having two compartments within the casing located side by side; a fan located in one drying compartment so that the air will be circulated by said fan 5 through said compartment, returning through the adjoining compartment and through the heating chamber.

3. The combination in a drier, of a casing; a drying chamber having two compartments located side by side; a partition partly dividing the two compartments; a heating chamber located at the back of the drying chamber and extending the full width of the drying chamber; heating coils in the 15 heating chamber; a circulating fan located at the rear end of one of the drying compartments, a horizontal shaft on which the fan is mounted; and tray supports in each drying compartment, said drying compartment being provided with doors.

4. The combination in a drier, of a casing;

a drying chamber having two compartments located side by side; a heating chamber at the rear of the casing and extending back of both compartments; a circulating fan for 25 circulating air through the drying compartment and the heating chamber; an air intake at the back of the heating chamber; and an air exhaust extending through the roof of the drier and in front of the heating com- 30 partment on the return side of the drier.

5. The combination in a drier, of two drying compartments located side by side; a heating chamber back of the drying compartments and extending below the said compartments, said heating chamber communicating with both drying compartments; and means for supporting the forward end of the drier, a fan located at a point so as to circulate air through the heating chamber 35 and both drying compartments. 40

ELWOOD B. AYRES.
